UNITED STATES PATENT OFFICE

2,449,591

PROTECTIVE PACKING MEANS

Kibbey W. Couse, Newark, N. J.

Application August 30, 1944, Serial No. 551,936

2 Claims. (Cl. 206—46)

1

This invention relates to new and improved means for packing and protecting containers carrying delicate instruments or fragile goods during handling and shipment, where this type of goods is in boxes or containers of different size and shape, and where several may be placed in one large packing box or in some more or less irregular compartment such as the fuselage of an aeroplane.

It has heretofore been customary, in packing small containers into a larger container or packing box, to stuff some sort of packing material, such as excelsior or paper, around the smaller containers, all of which is more or less inefficient and many times awkward where the space to receive the boxes containing the goods to be protected is irregular in shape.

It is therefore the principal object of my invention to provide a new and improved means of protection for the type of goods mentioned.

My present improvement contemplates the use of a flat, double-ended tube of considerable length and provided with an air valve whereby the tube may be blown up to a desired air pressure. The tube is made out of rubber or of a material having elastic properties. The flat tube, in deflated condition, is wrapped around the container carrying the goods to be protected, or in some cases it may be wrapped directly around the goods per se. Then, after the wrapping operation, air is forced through the air valve into the tubes, thereby giving a cushion effect far superior to any packing that has been in prior use. This manner of protecting containers or goods may be used to great advantage in paratroop work where containers are parachuted to the ground from an aeroplane, or jettisoned into the water.

In some cases where the containers or packing boxes are rectangular in shape and provided with my improved protecting tubes, they may be more easily handled by rolling them up and down ramps with a high degree of safety to the goods within the containers.

It will be readily understood that to remove the containers from a packing box or compartment wherein the goods are protected by my improved means, the tubes may be quickly deflated by means of the air valve or, in case of extreme emergency, the tubes may be punctured so as to permit easy removal of the containers carrying the goods.

With certain types of packing boxes, special means may be found necessary to insure that the air can flow through the various convolutions of the tube, all of which will be later explained, as well as other details which are shown in the annexed drawings wherein:

2

Figure 1 shows one form of blank from which the tube may be made.

Figure 2 shows the structure of Figure 1 folded up on the line 2—2.

Figure 3 shows the folded edge vulcanized.

Figure 4 shows the device of Figure 3 turned inside out like a stocking, wherein the vulcanized edge portion is wholly within the tube.

Figure 5 is a view similar to Figure 4, but showing the air valve attached thereto.

Figure 6 is a view similar to Figure 5, but with the ends vulcanized and the extremities pierced, ready to receive an eyelet as shown in Figure 7.

Figure 7 is a view showing one end of the completed tube.

Figure 8 shows the completed tube wrapped around a part of a container, with anchor means attached to the eyelets shown in Figure 7. Figure 8 also shows a packing box or compartment ready to receive the container with the deflated tube wrapped around it.

Figure 9 shows the complete assembly of the tube and box of Figure 8.

Figure 10 is a view similar to Figure 9 but with the tube inflated.

Figure 11 is a view of the lefthand end of Figure 9.

Figure 12 is a view of the left-hand end of Figure 10.

Figure 13 is a section on the line 13—13 of Figure 7, a section of the tube being shown on a support member.

Figure 14 is a sectional view of the tube of Figure 13 in inflated condition.

Figure 15 shows the form which the tube may take when placed between two packing boxes.

Figure 16 is similar to Figure 15, but one of the packing boxes having an irregular shape.

Figure 17 is a view similar to Figure 15, but showing a modified condition.

Figure 18 shows, partly in section, the tube of Figure 13 placed around a corner of a container.

Figure 19 is a view similar to Figure 18, but with the tube inflated to a certain degree.

Figure 20 shows a section through the tube in deflated condition and with a reenforcement associated therewith.

Figure 21 is a view similar to Figure 20 but showing the tube made of two pieces.

Figure 22 is a sectional view showing a modified form of construction wherein auxiliary support members are used within the tube.

Figure 23 is a view similar to Figure 22, but showing a different form of auxiliary support member.

Figure 24 is a view similar to Figure 18.

Figure 25 shows a form of reenforcement for the tube where the outside corner space is limited.

Figure 26 shows how the reenforcement member shown in Figure 25 is anchored at one end only of the tube.

Figure 27 is a sectional view through one end of the tube showing the application of the eyelet thereto.

Figure 28 shows one form of completed tube made in one piece as by moulding.

Figure 29 is a view on the line 29—29 of Figure 28.

Figure 30 shows a modified form of construction wherein a single piece of material is formed in such a manner as to produce two cooperative tubes.

Figure 31 is a view showing a plurality of tubes arranged between two walls or containers.

Figure 32 shows how the protecting tube may be permanently placed inside a compartment or box to receive containers carrying goods.

Figure 33 illustrates how various forms of containers may be packed within a given space.

In the various views, wherein like numbers refer to corresponding parts, 1 is a sheet of suitable elastic material which is made at both ends with a pair of projections 3. The sheet or strip 1 is adapted to be folded on the line 2—2 of Figure 1 as indicated in Figure 2, and then vulcanized or permanently sealed along the edge 4, after which the structure is turned inside out as indicated in Figure 4. An air valve 5 is shown attached, which may be done at any suitable time during the previously stated operation.

Then the tube is vulcanized or permanently sealed at its opposite ends 6 and 7, and the projections 3 have perforations 8 which may be made therein at the time the strip 1 is formed, or they may be made after the operation of Figure 5. Eyelets 9 are inserted and fastened in place in the projections 3. These eyelets are used for receiving binding cords or bands 10 which may be of the elastic type, to anchor the tube in place as shown in Figures 8, 9 and 10. The container 11 carrying the goods to be protected is wrapped with the completed tube as shown in Figure 8, after which it is set into the compartment or packing box 12 as shown in Figure 9. Then an air hose 13 is attached to the air valve 5 and the tube blown up to a certain pressure as shown in Figure 10.

The frictional engagement of the tube with the walls of the packing box or compartment 12 is such that with the binding cord 10 the tube need not in many cases be extended out over the ends of the container 11, but in some cases it may be so extended or another tube of suitable length may be inserted as shown in Figures 18 and 19, and 24, over the corners of the containers 11. Where the tube is likely to be pinched at a corner, thereby preventing the compressed air from filling the whole length of the tube, a fibrous member 14 may be used to prevent closure of the tube intermediate its length, as I have found in practice that an air space 15 will form around the member 14, and where this member is of a fibrous nature, air will seep through it into the tube and this will separate the sides of the tube so that it may be inflated.

In some cases a plurality of cords 14 may be used as shown in Figure 22, wherein the cords act not only to allow the tube to be blown up, but as reenforcing or additional cushioning means within the tube at some portion of its length where desired. This cushioning means

may take the form of cork or sponge rubber such as indicated at 16 in Figure 23. This construction is advantageous where the container is to be shipped into a war area, since the tubes might be punctured by some missile thereby letting the air out, in which case the sponge-like material or cord-type of material would still act as a shock-absorbing agent.

Where the tube is made in two pieces as in Figure 21, double air spaces 15 at each side may be provided. Where a single reenforcing member 14 is used longitudinally of the tube, it is bound only at one end around the eyelet 9 as indicated in Figure 26.

In the form of construction shown in Figure 29, the tube is moulded all in one piece, with reinforcing members 14 so that air spaces 15 are provided, whereby the tube may be sure of being inflated.

In Figure 30, the piece 1 is vulcanized or permanently fastened together at 17 to give, in effect, two tubes which may be used as occasion demands; or a plurality of tubes may be utilized in the manner as illustrated in Figure 31.

In Figure 32 the tube is provided with bands 18 so as to anchor the tube permanently in the corners of the packing box or receiver 12, so that removal of the containers 11 containing the goods may be carried out without disturbing the position of the tubes. In this construction, the tubes may be provided with the porous reenforcement member of the cord or sponge-type, so that air can be forced into all parts of the tube.

Figure 33 shows a plurality of various sizes and types of containers carrying the goods to be transported and each provided with the packing means heretofore described. These containers are shown in a compartment such as 19, illustrating the fuselage of an aeroplane where there is an irregular space to be filled. Here the tube may be inflated and rolled up and pushed into the space as shown at 20; or the tube may be inserted in a similar space in a deflated condition and then inflated afterward. Where the containers are of very large size, several tubes may be wrapped around them in a chain-like manner and each tube inflated to a different degree in order to conform to the special positions of the containers and the surfaces to be contacted.

From what has been said, it will be readily appreciated that the forms of the tube may be varied over a wide range to suit the conditions as explained, without departing from the spirit of my invention or the scope of the appended claims.

What I claim is:

1. Means for protecting containers and their contents at least during shipment comprising: a normally flat narrow two-ended belt like hollow air tight tubular body of flexible material adapted to be spirally wound in continuous contact against some part of a container during shipment and capable of assuming various shapes to suit conditions, said body having an air valve whereby the body may be inflated after being placed in protective position with respect to the container.

2. Means for protecting containers and their contents as set forth in claim 1, further characterized in that means are carried within the structure defined in claim 1 for insuring that the structure can be inflated and for adding to its shock-resisting properties.

KIBBEY W. COUSE
